BOTTLE AND CLOSURE THEREFOR

Victor S. Reynolds, Detroit, Mich., assignor, by direct and mesne assignments, to Victor Closure Corporation, a corporation of Michigan

Application March 20, 1939, Serial No. 262,834

4 Claims. (Cl. 215—21)

My invention relates to a new and useful improvement in a container and closure therefor, the closure being of tamper proof and of such a nature as to prevent refilling of the container.

It is an object of the present invention to provide a container and closure therefor so arranged and constructed that a free and easy emptying of the container may be effected, while at the same time, a tampering with the container or closure will effect a destruction of the closure.

Another object of the invention is the provision of a container and closure therefor so arranged and constructed that a refilling of the container, while the closure is in position thereon, is rendered impossible.

Another object of the invention is the provision of a container and closure therefor so arranged and constructed that when the closure is moved into position on the container, it is automatically locked thereon, and irremovable therefrom without first effecting a destruction or mutilation of the container or closure.

Another object of the invention is the provision of a closure of this type possessed of a minimum number of parts easily and quickly assembled, and which will be light, durable, economically manufactured, and highly efficient in use.

Other objects will appear hereinafter.

The invention consists in the various features illustrated and described in the specification and drawing, and such modifications and variations thereof as may suggest themselves to one skilled in the art.

In the drawing, Fig. 1 is a side, elevational view of a container showing the closure applied.

Fig. 2 is a sectional view taken on line 2—2 of Fig. 1.

Fig. 3 is a side, elevational view of the neck of the container.

Fig. 4 is a sectional view taken on line 4—4 of Fig. 1.

Fig. 5 is a sectional view taken on line 5—5 of Fig. 2.

Fig. 6 is a sectional view taken on line 6—6 of Fig. 2.

Fig. 7 is a vertical, longitudinal, central, sectional view through the closure showing it in inverted position.

Fig. 8 is a sectional view, taken on line 8—8 of Fig. 3.

As shown in the drawing, the container 9 is provided with a neck 10 extending outwardly from one end, this neck being provided with the threads 11 and 12 spaced from an outwardly

projecting flange 13. Extending between the threads 11 and 12 and the flange 13 are abutment plates 14 and 15 formed integral with the neck 10. Positioned slightly below and extending beyond the flange 13 is a base-forming flange 16 against which the end of the closure engages when in closing position. As shown clearly in Fig. 4, one side of each of the abutment plates 14 and 15 is formed beveled to provide an undercut 17.

The closure comprises a tubular body 18 which is provided with a tapered portion 19 terminating in an enlarged end portion 20. This tapered portion 19 provides a surface on which advertising or similar display may be displayed. This tubular body 18 terminates in the outer terminal portion 21 which is of slightly less diameter than the main body, and adapted to receive a cap 22 which may be pressed thereon, and removed therefrom with ease.

The tubular body 18 toward the outer end is provided with the thickened portion 23, on the inner surface of which is formed a plurality of grooves 23', this enlarged or thickened portion 23 serving as an abutment or shoulder on the cup-shaped closure 24 which is insertible as a press fit into the bore 25 of the enlarged portion 23. This cup-shaped closure 24 carries at its open end an outwardly projecting peripheral flange 26 having an upturned rib or bead 27 at its margin, so as to prevent the thrusting of wires or similar articles inwardly through the grooves 23'. The inner face of the tubular body 18 at the tapered portion 19 is cut away as at 28 to provide a shoulder against which the outwardly projecting flange 29 of the seat-forming ring 30 may engage, this ring 30 having at its inner end an inwardly projecting flange 31 surrounding the concentric opening 32. Adapted to engage the surface of the flange 31 is a conical valve 33 which, when resting upon the upper surface of the flange 31 so as to close the opening 32, will project at its tapered end inwardly of the cup-shaped closure 24. The ring 30 is pressed into the tubular body as a press fit, and engaging the lower face of the ring 30 is a gasket 34.

The enlarged portion 20 is provided on its inner face with a pair of oppositely positioned bosses 35, the side walls of which are undercut as at 36 for receiving an end of an arcuate spring 37 having a tongue 38 pressed outwardly therefrom.

In mounting the closure on the neck, the closure is assembled as shown in Fig. 2, and then

placed downwardly over the neck while the bosses 35 are in relation with the spaces between the threads 11 and 12. A rotation of the closure relatively to the bottled neck will then bring these bosses 35 into engagement with the under surface of the threads 11 and 12, which will serve to move the closure axially so as to clamp the ring 30 against the outer face of the bottled neck, and at the same time, the end of the closure will be brought into engaging position with the flange 16, the flange 13 engaging the inner face of the bosses 35. As it screws into position on the neck, and as the closure moves into its final sealing position, the outwardly punched tongue 38 of the spring 37 will ride over abutment plates 14 and 15, and snap into position behind them so as to prevent reverse rotation of the closure relatively to the neck, thus preventing removal of the closure from the neck. In this manner, the closure is securely locked in position on the neck of the container and in sealing relation thereto. When the container is set in upright position, the conical valve 33 will serve to close the open end of the container neck, and when the container is tipped upwardly, this valve 33 will move downwardly so as to project farther into this cup-shaped closure 24 and permit escape of the liquid from the bottled neck. This liquid will flow around the flange 26 which is of less diameter than the tubular body 18, and then pass through the grooves 23' outwardly of the closure. When the container is moved to upright position, the valve 33 will prevent passage of liquid to the container, so that refilling of the container is thus prevented.

Any undue axial pressure on the closure 24 inwardly of the tubular member 18 will force the closure inwardly against the valve 33 so as to lock it on its seat. Thus the member 24 affords a means of guarding against undue tampering with the closure, and also affords means for destroying the operativeness of the closure when the container is empty.

It is proposed that the closure be formed from a composition material, and molded. By forming the closure in this manner, it is but necessary to mold four separate parts, namely, the members 18, 24, 33, and 30, all of which may be easily and quickly assembled in operative position.

With this form of construction it becomes possible to not only have a container and closure therefor highly efficient in use, and economically manufactured, but also one which may be rendered highly attractive in appearance.

What I claim as new is:

1. A container closure of the class described, comprising: a tubular body; a plurality of inwardly directed spaced ribs extending around the inner faces of said body, adjacent its outer end, said ribs being of equal length, and terminating outwardly from the center of said body to define with their inner ends a bore; a cup-shaped member insertible into said bore with the closed end thereof projecting outwardly; a flange on said cup-shaped member for engaging against the sides of said ribs, and limiting outward axial movement of said member relative to said tubular body; a valve seat-forming member having an opening formed therein, and posi-

tioned in said tubular body in spaced relation to the inner end of said cup-shaped member; and a valve member tapered longitudinally of its axis, and engageable at its base with said valve seat, and forming a closure for said opening; the tapered end of said valve projecting inwardly of said cup-shaped member.

2. A closure of the class described, comprising an elongated tubular body having an upper end 10 and a lower end; a closure insertible into said body, and engageable as a press fit in said upper end for closing the same, said tubular body having a plurality of passages extending around said closure for permitting flow of liquid through said tubular body around said closure; a valve seat engageable as a press fit in said tubular body, and positioned in spaced relation to the lower end of said closure; a conical valve engageable at its base with the upper face of said seat for closing the same, and projectible at its upper end into a recess formed in the inner end of said closure; and a flange projecting outwardly from the inner end of said closure for overlying the inner ends of said passages.

3. A closure of the class described, comprising: an elongated tubular body having an upper end and a lower end; a closure insertible into said body, and engageable as a press fit in said upper end for closing the same, said tubular body having a plurality of passages extending around said closure for permitting flow of liquid through said tubular body around said closure; a valve seat engageable as a press fit in said tubular body, and positioned in spaced relation to the lower end of said closure; a conical valve engageable at its base with the upper face of said seat for closing the same, and projectible at its upper end into a recess formed in the inner end of said closure; a flange projecting outwardly from the inner end of said closure for overlying the inner ends of said passages; and an axially directed bead on the periphery of said flange.

4. A closure of the class described comprising: an elongated tubular body having an upper end and a lower end; a plurality of inwardly directed, spaced ribs extending around the inner face of said body adjacent its upper end and terminating at opposite ends inwardly of the opposite ends of said body, said ribs terminating outwardly from the center of said body to define with their inner ends, a bore; a cup-shaped member inserted as a press-fit into said bore from the lower end of said tubular body with the closed end of said cup-shaped member projecting outwardly; a peripheral flange on the open end of said cup-shaped member, overlying the ends of said ribs and limiting outward thrust of said cup-shaped member relatively to said body; a valve seat-forming member having an opening formed therein and positioned in said tubular body in spaced relation to the open end of said cup-shaped member; and a valve member tapered longitudinally of its axis and engageable at its base with said valve seat for forming a closure for the opening therethrough, the tapered end of said valve projecting inwardly of said cup-shaped member, the thrusting inwardly of said cup-shaped member a predetermined distance effecting a securing of said valve in closing position on said valve seat.
